UNITED STATES PATENT OFFICE.

DANIEL BERKELEY UPDIKE, OF BOSTON, AND BERTRAM G. GOODHUE, OF CAMBRIDGE, MASSACHUSETTS.

DESIGN FOR A FONT OF PRINTING-TYPE.

SPECIFICATION forming part of Design No. 25,979, dated August 25, 1896.

Application filed October 11, 1895. Serial No. 565,425. Term of patent 7 years.

To all whom it may concern:

Be it known that we, DANIEL BERKELEY UPDIKE, residing in Boston, in the county of Suffolk, and BERTRAM G. GOODHUE, residing in Cambridge, county of Middlesex, State of Massachusetts, citizens of the United States, have invented and produced a new and original Design for a Font of Printing-Type, of which the following is a full, clear, and exact description.

The design relates generally to the configuration of the capitals and lower-case letters, including ligatured letters, the character "&," "\$" and "£" marks, punctuations, &c. The special object of the invention is to produce a series of upper and lower case letters, &c., suitable for the printing of books which have large pages of type (such as folio volumes of the classics in Latin and English, portions of the *Book of Common Prayer*, and such like works) that shall furnish when set up a page of solid, strong, and uniform blackness, which, while holding this uniform color, shall be perfectly clear, readable, and easy to the eye.

This design provides a font of type which avoids the irregularities of what are commonly known as "job" fonts of type, while possessing their blackness, and possesses much simplicity and clearness with great strength and uniformity in color. To attain this, the letters are but little modeled, keeping a heaviness of line, which, while not uniform throughout the letter, is extremely marked. This produces a solid and black effect to the eye when presented in mass.

The design avoids all angular lines as much as possible and substitutes curves, the serifs at the top and bottom of the ascending lines of capital letters having an easy blending curve introduced in the ascending shaft of

the horizontal serif. This gives the ease and clearness to the eye that is desired. The weight of the letter comes chiefly on the lower left-hand stroke. The circles or loops of the letters of the lower-case o, d, q, p, g, œ, e, a, c, and other letters of this class have elliptical centers and cant toward the left. This is true also of the capitals O, G, C, Q, &c. For the punctuation the periods are lozenge-shaped, not quatrefoil. Round dots are used for the i's. The lower-case letters avoid all angular serifs at the bottom of the f, h, i, k, l, m, n, p, q, r, and x and at the top of v, w, and y. They also avoid all abrupt angular slants from the left to right at top of letters such as d, b, p, i, j, k, l, and u; and by this combination of ease of line, weight upon the lower left-hand corner of the letter, and a slight cant in the rounded letters themselves, the effect of strength and thickness is produced, together with a slight irregularity of effect.

In the accompanying drawing, forming a part hereof, we show the alphabet both in the capitals and lower-case letters, the \$-mark, £-mark, paragraph-mark, bracket, parenthesis, exclamatory-mark, query, hyphen, semicolon, comma, period, and dash, together with the numbers 1 to 9, the cipher, and letters QU and Qu cut together, as the tail of the Q extends beneath the letter U. æ and œ, fi, fl, ff, ffi, ffi, are cut as logotypes. The capital letters also include Æ and œ cut together.

Having described our invention, we claim—

The design for a font of printing-type substantially as shown and described.

DANIEL BERKELEY UPDIKE,
BERTRAM G. GOODHUE.
